[57] CLAIM

The ornamental design for a wristwatch, as shown and described.

DESCRIPTION

FIG. 1 is top and right perspective view of a wristwatch showing my new design;

FIG. 2 is a top plan view thereof, the rear being flat and unornamented.

The watchcase is illustrated as having the geometrical configuration of an annular segment of a golf ball and a flat dial and flat backside. The watchcase has a golf club mounted thereon.
